STOCKING PROTECTOR

Filed Sept. 17, 1931

Fig. 1.

UNITED STATES PATENT OFFICE

ADELAIDE HEELAN, OF ST. LOUIS, MISSOURI, ASSIGNOR OF ONE-HALF TO JAMES G. JONES, JUNIOR, OF ST. LOUIS, MISSOURI

STOCKING PROTECTOR

Application filed September 17, 1931. Serial No. 563,439.

This invention relates to a stocking protector and one object of the invention is to provide a stocking protector which in some respects resembles a spat and may be very 5 easily carried in a hand bag when not in use, and quickly applied if a person is caught out during a rain storm.

Another object of the invention is to so 10 form the stocking protector that when it is in use it will cover the ankle and upper portion of a person's foot and thereby prevent the stocking from becoming splashed by rain or by water splashed by automobiles and other vehicles moving along a street.

15 Another object of the invention is to so form the protector that it has a front opening adapted to be closed by interengageable fasteners of the zipper type and thereby permit the protector to be opened for practically 20 its full length while it is being put on and the front opening then closed and very firmly secured in a closed position.

The invention is illustrated in the accompanying drawing wherein:

25 Figure 1 is a perspective view showing the improved stocking protector in use,

Figure 2 is an enlarged sectional view taken transversely through the stocking protector along the line 2—2 of Figure 1,

30 Figure 3 is a fragmentary sectional view through the body portion of the stocking protector and the securing strip thereof which extends beneath a person's shoe, and

Figure 4 is a fragmentary view looking at 35 the inner face of the lower end of the front portion of the stocking protector.

The improved stocking protector comprises a body 1 which in some respects resembles a spat of the type worn by some 40 people in order to protect the ankles and upper portions of the feet during cold weather.

This body portion is preferably formed of waterproof fabric as it is to protect a person's stocking from becoming soiled by rain water or by water splashed from puddles in a street. The two sections 2 of the body are of duplicate construction and are so shaped that the body will fit snugly about a 50 person's ankle and the upper portion of a

foot when the device is worn. The rear edges of the sections are folded inwardly as shown at 3 and stitched together as shown at 4, and the front edges of the sections have their lower ends stitched together as shown at 5 55 to form a relatively narrow bridge piece. The stitching 5 only extends the width of the bridge piece and for the remainder of the length of the body the front edges of the two sections are free from each other, thereby 60 permitting the protector to be opened at its front and very easily fitted into place as shown in Figure 1 with the strap 6 extending beneath the instep portion of a shoe.

In order to releasably secure the front 65 edges of the protector in a closed portion there has been provided interengaging fasteners 7 of the zipper type which are carried by fabric strips 8. These strips 8 extend along the front edges of the two sections in overlapping relation to the underfaces thereof and are firmly stitched in place as shown at 9. By this arrangement it is merely necessary to thrust a person's foot downwardly 70 through the protector until the protector is in its proper position and then draw the actuating element 10 upwardly and the front opening 75 will be firmly held closed.

A tongue 11 which serves as a guard for the front opening and a shield for the fastener extends longitudinally of the front opening in bridging relation thereto and is secured adjacent one of its side edges by the stitching which serves to retain the fastener strip 8 80 in engagement with a side section of the protector. The lower end of the tongue is spaced 85 upwardly from the lower edge of the bridge piece, as shown, so as not to interfere with the flexibility of said bridge piece and thus permit the latter to conform to and fit snugly 90 against the vamp of the shoe. It should also be noted that the strips 8 extend downwardly beneath the bridge piece and a line of stitching 12 extends transversely through said 95 bridge piece and through the lower edge portion of the tongue and the depending portions of the strips 8 overlapped thereby. Therefore the portion of the protector below the front opening will be greatly reinforced and 100

danger of its tearing below the front opening prevented.

I have therefore provided a stocking protector which is strong in construction and 5 may be very easily put on or taken off. It will also be noted that the stocking protector will be light in weight and when not in use may be folded into a small mass and placed in a hand bag.

10 What is claimed is:

A stocking protector comprising a body of waterproof material shaped to fit about the ankle and cover the upper portion of a person's foot, said body being formed of mating 15 sections having their rear edges united and their front edges separated to form a front opening leading from the upper edge of the body and terminating in spaced relation to its lower edge to form between said lower 20 edge and opening a flexible bridge piece connecting the front edges of the sections at the lower portion of the body interengaging fastening devices having attaching strips overlapping the inner faces of the body at the 25 opposite sides of the front opening and extending downwardly beneath the upper edge of the bridge piece a tongue across the front opening and fasteners extending longitudinally of the body and being of greater width 30 than the fasteners and their attaching strips and having its lower end spaced upwardly from the lower edge of the bridge piece and bearing against the inner face thereof lines of stitching extending longitudinally of the 35 attaching strips and engaged through the body between the upper edge of the body and the upper edge of the bridge piece, one of said lines of stitching also extending through a side portion of said tongue, and a line of 40 stitching extending transversely across the lower end of the tongue and engaged through the bridge piece and adjacent portions of the attaching strips to reinforce the body at said bridge piece.

45 In testimony whereof I affix my signature.
ADELAIDE HEELAN. [L. s.]
